Electric Company, Incorporated, New York,
N. Y., a corporation of New York

Application February 12, 1947, Serial No. 728,029

26 Claims. (Cl. 179—99.2)

1

This invention relates to a telephone calling device for use in an automatic telephone system and more particularly to a dial operated impulse sender in which the dial is rotated only in one direction.

It is an object of the present invention to provide an improved calling device capable of being actuated at a rapid rate.

In accordance with one embodiment of the present invention, the device is provided with a finger wheel dial rotatable in one direction through dialing movements of various predetermined lengths corresponding to the various digits of a number to be dialed. The dial is associated in coaxial alignment with a rotatable pulsing wheel of a pulsing mechanism which is connected to a governor and produces a predetermined number of pulses at regular spaced intervals for each complete revolution of the wheel. The wheel is stressed for rotation by a torsion spring interconnected between the pulsing wheel and the dial and is engageable by a plurality of normally inoperative stop members capable of stopping the pulsing wheel in a plurality of positions whereby the wheel may be stopped after the production of a predetermined number of pulses. The stop members are sequentially actuated by a cam member rotatable with the dial so that one of the stop members is rendered effective to stop the pulsing wheel after it has moved through a predetermined arc and has produced a selected number of pulses, as determined by the dialing movement of the finger wheel dial, the number of pulses being always one more than the numerical value of the digit dialed. The dial is movable in a reverse direction at the end of each dialing movement for a relatively short distance to set up and render effective selected ones of a plurality of normally ineffective cam members at points in angular relation to each other corresponding to the angle of rotation of successive dialing movements of the dial to cause the actuation of a rotatable circuit control means for rendering ineffective the first or extra pulse of each digit series of pulses and thereby separate each series of digit pulses from the others. This arrangement permits the rapid actuation of the dial and the speedy completion of the number dialing operation and results in the setting up of the cam members in a sequence or pattern corresponding to the sequence or pattern of the dialing movements of the dial while the pulses produced by the pulsing mechanism at regular governor-controlled intervals are separated by the action of the dial conditioned cam members into separate

2

series with the number of pulses in each series corresponding to the digits of the number dialed.

The invention will be more fully understood from the following description when considered in connection with the accompanying drawings, in which

Fig. 1 is an enlarged front view of the calling device showing, in dotted lines, the radially movable stop members set in various radial positions and the dial actuated members for effecting the setting of the stop members;

Fig. 2 is a perspective view of the dial actuated lever rigidly connected to the dial for camming the stop members axially;

Fig. 3 is a perspective view of the dial actuated member for camming the stop members radially outwardly;

Fig. 4 is a vertical, axial, sectional view of the device;

Fig. 5 is a fragmentary rear elevational view of the device;

Fig. 6 is a fragmentary sectional view of the device showing the dial actuated member camming a stop member radially into engagement with an abutment member on the pulsing wheel;

Fig. 7 is a vertical sectional view taken on the line 7—7 of Fig. 4 showing the arcuate stop members in their various positions and the dial actuated members, the abutment member and a switch actuating member in engagement therewith;

Figs. 8 and 9 are fragmentary views similar to Fig. 7 showing parts of the mechanism in changed positions;

Fig. 10 is a sectional view taken on the line 10—10 of Fig. 4;

Fig. 11 is a detail view of the abutment member and the switch actuating lever secured thereto detached from the pulsing mechanism;

Fig. 12 is a sectional view taken on the line 12—12 of Fig. 4 showing a governor for controlling the rate of transmission of the pulses;

Fig. 13 is a horizontal, axial, sectional view of the device;

Fig. 14 is an elevational view of the portion of the device showing the abutment member and the switch actuating lever carried by the pulsing mechanism in engagement with the stop members and showing the dial actuated members in one position in their relation to the stop members before the dial and the lever rotatable therewith have been reversely rotated;

Fig. 15 is a view similar to Fig. 14 showing some of the parts in changed position after the lever has been moved in the reverse direction;

Fig. 16 is a schematic view illustrating the relation of the pulsing contact springs and a circuit control switch connected to the telephone;

Fig. 17 is a fragmentary view in perspective of the stop members;

Fig. 18 is a fragmentary view in perspective showing the dial actuated members in their normal positions in engagement with the arcuate stop members; and

Fig. 19 is a view in perspective of the abutment member and the pivoted switch actuating lever carried thereby detached from the pulsing mechanism, the parts being the same as those shown in Fig. 11.

As shown in the drawings, particularly in Figs. 1, 4 and 13, the calling device has a finger wheel or dial 29, which is secured to a shaft 21 for rotation about its axis and is connected through a torsion motor spring 22 to a rotatable pulsing mechanism 23 (Fig. 13) comprising a toothed pulsing wheel 24, a pulsing lever 25 and a pair of pulsing contact springs 26 and 27. The dial 20 is provided with twelve equally spaced apertures or finger holes 28 disposed adjacent the outer edge thereof (Fig. 1). It is further provided with a central non-circular aperture 30 for receiving a non-circular portion 31 of the shaft 21, to which the dial 20 is secured by means of a lock nut 34, which engages a reduced threaded end 35 of the shaft 21. The shaft 21 is journaled in a bearing member 37 fixed to a supporting plate 38 having a flange 39 fitting over a cylindrical wall 40 of a housing 41 and secured thereto by screws 42. The dial 20 and a lever 43 secured to the opposite ends of the shaft 21 serve to prevent longitudinal or axial displacement thereof.

A number plate 44, fixed to the plate 38, has printed thereon a series of ten digits or numbers ranging from 0 to 9, inclusive, and arranged as shown in Fig. 1 in alignment with the finger hole 28 of the dial 20. A finger stop 45 (Figs. 1 and 13) secured to the flange 39 of the plate 38 is positioned to overlie a portion of the dial 20 and serves to engage the finger of the person calling and limit the turning movement of the dial 20 during a dialing operation. The numbers on the plate 44 are arranged so that the person calling, by inserting his finger in a finger hole opposite a selected number on the number plate 44 and turning the dial 20 until his finger engages the stop 45, will rotate the dial through an arc that will effect the operation of the pulsing mechanism 23 through a similar arc and transmit a number of pulses corresponding to the digit selected.

The shaft 21 (Fig. 4) is recessed to receive the torsion spring 22 therein, one end 46 of which is firmly secured to the shaft 21. The other end 47 of the torsion spring 22 is bent diametrically across the spring and is connected to a shaft 48 of the pulsing mechanism 23 by fitting into a slot 49 in the end thereof. Before the end of the spring 22 is connected to the shaft 48, it is turned through several revolutions to create a torque tending to rotate the dial 20 and the shaft 48 in opposite directions. The shaft 48 is provided with a circular disc or flange 52 and is journaled in a bearing member 53 secured to a supporting wall 54 of the housing 41. A washer 55 and a lock nut 56, mounted on the end of the shaft 48, and the flange 52, act to prevent longitudinal displacement of the shaft 48 in the bearing member 53.

Secured to the flange 52 is the toothed pulsing wheel 24, which is provided on its periphery with

twelve equally spaced teeth 61 (Figs. 4, 10 and 13). Upon rotation of the pulsing wheel 24, the teeth 61 engage and move an arm 62 of the pulsing lever 25, which is pivotally mounted on a pin 63 carried by brackets 64 and 65 secured to the wall 54 of the housing 41. Extending on the opposite side of the wall 54 from the arm 62 of the pulsing lever 25 is an arm 66 supporting a roller 67, which engages one end of the contact spring 26 (Figs. 5 and 13).

The contact springs 26 and 27 are supported on a block of insulation 68 (Fig. 13) mounted on the wall 54 and are electrically connectible through a circuit control switch 69, also mounted on the block 68, to line terminals of the calling or telephone circuit (Fig. 16). For the sake of clearness, the wiring connecting the various contact springs and terminals is omitted from the structural portions of the drawings. The contact spring 26 is biased to normally engage the contact spring 27 and to hold the pulsing lever 25 so that the arm 62 thereof is in the path of the teeth 61 of the pulsing wheel 60.

In order to control the rate at which the pulses are transmitted, a governor 70 is provided (Figs. 4 and 12). The governor 70 is mounted within a drum 71, which is secured to and projects rearwardly from the wall 54 of the housing 41. The rear wall 72 of the drum is centrally apertured to receive one end of a governor shaft 73, the other end of which is journaled in a bridge member 74 (Fig. 10). A cross arm 75 is fixed to the shaft 73 and carries a pair of arcuate weights 76 and 77 pivoted to the ends of the cross arm by pins 78 and 79. The weights 76 and 77 are maintained in their normal position by leaf springs 80 and 81 secured to one end, respectively, of each of the weights 76 and 77 and which abut against stop member 82, carried by the cross arm 75. Friction studs or shoes 83 and 84, carried, respectively, by the weights 76 and 77, move outward with the weights and engage the inner surface of the drum 71 when the shaft 73 is rotated fast enough to overcome the action of the springs 80 and 81 and act to retard the movement of the shaft and limit the rotation thereof to a predetermined rate.

The governor shaft 73 has secured thereto a gear 86 (Figs. 4 and 10) which meshes with a gear 87 fixed to a shaft 88, the ends of which are journaled in the wall 54 and the bridge member 74. A gear 89 is fixed to the shaft 88 and meshes with a ring gear 90 secured to the flange 52 on the shaft 48 of the pulsing mechanism 23. Upon rotation of the pulsing mechanism 23, the governor 70 is also rotated through the gear drive just described, to control the rate of rotation of the pulsing mechanism and the frequency at which the pulses are produced.

To stop the movement of the pulsing mechanism 23 after the completion of a pulse transmitting operation, there is fixed to the flange 52 of the pulsing mechanism a cooperating stop element or abutment member 95 (Figs. 4, 7, 10, 11 and 19), which is adapted to engage and be stopped by any one of a plurality of non-rotatable radially movable arcuate stop members 96 (Figs. 7, 8, 9 and 17). The stop members 96 are moved radially outwardly into the path of the abutment member 95 by a camming member 97 rotatable on the bearing 37 with the dial 20, as will be more clearly described hereinafter. The abutment member 95, as shown most clearly in Fig. 19, comprises an arm 98 extending radially from a ring-like body portion 99, which is secured to

the wheel 24 and the flange 52 of the shaft 48. The arm 98 is provided with an axially extending portion 100 and a forward arcuate portion 101, which terminates in a radially disposed end 102 engageable with the stop members 96.

There are twelve stop members 96 (Figs. 7 and 17) equally spaced and arranged in a circle with the stop surfaces or end edges 104 thereon adapted to engage the abutment 95 and stop the pulsing mechanism after a movement thereof sufficient to produce one complete pulse or a plurality of complete pulses. The members 96 are formed on the ends of flexible irregularly shaped arms 105 extending outwardly from a central disc portion 106 and comprise a unitary structure formed from a sheet of spring steel. The disc 106 is centrally apertured and is secured to the stationary bearing member 37 (Figs. 4 and 13). The flexible arms 105 comprise flat radial portions 107, the outer ends of which are bent at right angles and have extending therefrom angularly disposed portions 108, which, at their ends, are formed with short longitudinally extending portions 109 on which the members 96 are formed.

Each of the members 96, when viewed from above (Figs. 14 and 15), is oblong and has straight end edges 104 and 110 substantially parallel to the axis of the device and has front edges 111 and 112 separated by the longitudinally extending portion 109 of the supporting arms 105. The front edge 111 is perpendicular to the edge 104 and the front edge 112 is inclined with respect to the edges 110 and 111. The rear edge is irregularly shaped to form a cam 113 having end portions inclined with respect to an intermediate straight portion.

The arcuate members 96 are stressed longitudinally forward toward the dial 20 and radially inward by the flexible arms 105 and are movable radially to occupy any one of three positions, as indicated in Fig. 7, a radially outer position 117, a radially intermediate position 118, and a radially inner position 119. The forward edges 111 of the members 96 are urged against and are engaged by either of the relatively spaced vertical faces 120 or 121 of arms 122 formed on the outer edge of a disc 123, which is secured to the bearing member 37 (Figs. 4, 7, 13, 14 and 18). Shoulders 124 formed on the arms 122 engage the inner arcuate surface 125 of the members 96 adjacent the edge 111 and serve to hold the members 96 in their intermediate positions 118 and the edge surfaces 127 of the disc 123 between the arms 122 act to limit the inward movement of the members 96 and determine their inner radial positions 119.

The members 96 have several functions. When in the radially outer position 117, they serve to engage the abutment 95 and stop the rotation of the pulsing mechanism; when in the radially intermediate position 118, they serve to stop the reverse movement of the dial 20, as hereinafter described; and when in the radially inner position 119, they serve to actuate the circuit control switch 69, as hereinafter described.

The rotatable actuating or camming member 97 (Figs. 3, 4, 6, 7, 8 and 18), in rotating with the dial 20, operates to move successively each arcuate member 96 to its outer radial position 117. On the outer end (Fig. 7) of the actuating member 97, a roller 132 is rotatably mounted on a pin 133 and is adapted to engage the inner surfaces 125 of the members 96. The member 97 (Fig. 4) is apertured at 134 and is rotatably

mounted on the outer bearing surface 135 of the bearing member 37 and is retained axially on the bearing 135 against the disc 123 by the lever 43. In response to the rotating movement of the dial 20, the camming member 97 is moved about the axis of the device through the action of the lever 43, a part of which is offset longitudinally into the plane of the member 97 to provide an edge or surface 136 for engaging the edge of the member 97 when imparting rotation thereto (Figs. 2, 4, 8 and 18). The member 97 is counterbalanced by an extension 137 of the member and remains in whatever position it is moved to by the lever 43.

As the camming member 97 is rotated about the axis of the device, in response to the movement of the dial 20, the roller 132 carried thereby will engage the inner arcuate surfaces 125 of the members 96 and move successive members 96 outwardly to their radial outward positions 117, where each member 96 successively is in the path of and is effective to stop the abutment 95. After the following arcuate member 96 has been moved outwardly (Fig. 8), the roller 132 as it advances with the member 97, will disengage itself from the preceding stop member 96 and allow that member to be moved radially inward by the spring action of the flexible arm 105 to its intermediate position 118, where the inner arcuate surface 125 thereof adjacent the edge 111 will engage and be stopped by the shoulder 124 of the arm 122. As the member 96, which has been engaging the abutment member 95, moves inwardly, it disengages itself from the end 102 of the abutment member 95 and the abutment member 95 and the pulsing mechanism 23 are then free to rotate in a clockwise direction, as viewed from the front, under the action of the torsion spring 22 until the member 95 engages another stop member 96 that has been moved into its path. The individual members 96 are thus successively moved into operative position in the path of the abutment member 95 and moved from the operative position out of the path of the abutment 95 as the dial 20 and the camming member 97 are rotated. The outwardly displaced one of the stop members 96 which is operative to engage the abutment 95 is thus effectively advanced clockwise around the device in steps of 30° in response to the rotation of the dial 20 to stop the pulsing mechanism 23, upon completion of the pulsing operation, in a predetermined relation to the dial and thereby limit the rotation of the pulsing wheel to arcuate movements corresponding to those of the dial.

The dial, as previously stated, is provided with twelve equally spaced finger holes 28 arranged in angular relation to each other of 30° and corresponding in number and angular relationship to the stop members 96 and to the teeth 61 on the pulsing wheel 24. With this arrangement, it will be seen that if a finger is inserted in a finger hole of the dial 20 and moved from one number position to another to rotate the dial through an arc of 30°, the dial actuated members 43 and 97 will cause the operative stop member 96 engaging the abutment member 95 to be moved to its intermediate position after the following stop member has been moved to its outer position and thus permit a rotary movement of the spring stressed abutment member 95 and the pulsing wheel 24 through a pulse-increment of 30° to actuate the pulsing contacts 26 and 27 once, thereby producing one pulse. Thus, for

each pulse-increment of rotation of 30° of the dial, the stop members 96 are conditioned to allow a corresponding pulse-increment of rotation of 30° of the pulsing wheel and the production of one pulse.

The torsion spring 22, as previously described, is initially adjusted to produce a predetermined torque between its ends to stress the pulsing mechanism 23 for rotation in a clockwise direction and stress the dial 20 for rotation in a counterclockwise direction, as viewed in Fig. 1. The rotary movement of the pulsing mechanism 23 is arrested by the engagement of the abutment member 95 with one of the arcuate stop members 96, as previously described, and to prevent substantial reverse movement of the dial 20 at the end of each digit dialing movement, the lever 43, which is secured to and rotates with the dial 20, is provided with an abutment or stop lug 140 (Figs. 1, 2, 4, 7, 8, 9 and 18) adapted to engage and be stopped by the preceding stop member 96, which has been moved from its outer position to its intermediate position behind and in the path of reverse movement of the stop lug 140 (Figs. 9 and 18). As the lever 43 is rotated forwardly, the members 96 are cammed radially outwardly from their intermediate positions 118 in front of the lug 140 of the lever 43 by the roller 132 and then returned to their intermediate positions 118 in back of the lug 140 after the lug has passed thereunder.

The short reverse movement of the dial 20 and the lever 43 at the end of each digit dialing movement is utilized to condition the arcuate members 96 for actuating circuit control means which operates to connect the pulsing spring contacts 26 and 27 to the telephone line and disconnect the receiver and the transmitter from the line during the transmission of the pulses and to disconnect the pulsing contacts 26 and 27 from the line and reconnect the receiver and the transmitter to the line on completion of the transmission of the pulses, as will be described herein-after.

The lug 140 of the lever 43 (Figs. 14 and 18) is provided with an inclined surface 141, which, during the reverse movement of the member 43, is adapted to engage the inclined edge 112 of the stop member 96 in its path and cam the member 96 rearwardly off the shoulder 124 of the arm 122. When cammed off the shoulder 124, the member 96 is moved to its radial inner position 119 by the spring arm 105 and it also serves to stop the reverse movement of the lever 43 and the dial 20.

Upon clockwise rotation of the dial 20 by the calling party, the lever 43 moves into engagement with and moves the camming member 97 until the dial 20 has reached the end of its selected arc of dialing movement, at which time the roller 132 of the member 97 will come to rest engaging an arcuate member 96 on its inner arcuate surface 125 (Fig. 9) intermediate its ends after having moved that member 96 to its outer position 117 while the preceding member 96 has moved from its outer to its intermediate position 118 behind the lug 140 on the lever 43 (Figs. 7, 8, 14, 15 and 18). Upon release of the dial 20 by the calling party at the end of each digit dialing movement, the torsion spring 22 moves the dial 20 and the lever 43 reversely or counterclockwise until the portion 140 of the lever 43 engages the stop member 96 in its path, which member 96 limits the reverse travel of the lever 43 to a very short movement and is, itself, caused to be moved

5 to its inner position 119 thereby. The camming member 97 remains stationary while the lever 43 is moved reversely so that the edge 136 of the lever 43 is separated from the member 97 at the end of the dialing operation (Figs. 1 and 7).

The roller 132 on the camming member 97, as it rotates and engages successive members 96 and moves them sequentially to their outer positions 117 and then releases them so that they may 10 move to their intermediate positions, serves, on the following rotation of the member 97, to reset to their intermediate positions 118 the members 96 that have been moved to their inner positions 119. The members 96 are thus set up in their inner positions 119 for one revolution of the camming member 97 and the pulsing mechanism 23, after which they are restored to their intermediate position 118 by the rotatable camming member 97 as described.

20 When the members 96 are in their radial inner positions 119, the cams 113 thereon are in the path of a rotatable lever 146 of a circuit-controlling mechanism, which lever rides up on and off the cams 113 to effect, respectively, the alternate disconnecting from and connecting to the telephone circuit of the pulsing contacts 26 and 27 and simultaneously therewith the alternate connecting to and disconnecting from the line of the transmitter and the receiver. The circuit 25 controlling means, in cooperation with the operative cams 113, serves to connect the pulsing contacts 26 and 27 to the line circuit and to disconnect the transmitter and receiver from the line during the transmission of each digit series of pulses and to disconnect the pulsing contacts 26 and 27 from the line and to reconnect the receiver and transmitter to the line on completion of the transmission of each digit series of pulses. The circuit controlling means comprises the switch 30 40 69 (Figs. 4 and 13), a switch operating rod 145, and the switch operating lever 146, which lever is mounted for rotation with the pulsing device 23.

The switch operating lever 146 extends diametrically across the device and has a T-shaped 45 end 147, which is secured in spaced relation, as by spacers and rivets, to a similar T-shaped end 148 formed as a part of the abutment member 95 (Figs. 4, 7, 11 and 19). Adjacent its T-shaped end, the lever 146 is reduced in thickness to permit 50 it to be flexed near its fixed end and permit the free end thereof to be reciprocated. The free end of the lever 146 is slotted to receive a roller 150, which has a conical portion 151 and which is rotatably mounted on a pin 152 fixed to the lever. 55 The intermediate portion of the lever 146 is enlarged to form an annular yoke 153 encircling the shaft 48 and is provided with a finger-like portion 154 projecting into an aperture 155 in the shaft 48.

60 The switch operating lever 146, in its normal or unflexed position, occupies a forward position, indicated in dotted lines in Fig. 4. This occurs when the members 96, which are radially aligned with the lever 146, are in their intermediate or outer positions 117 and 118, in which positions there is no engagement of the members 96 with the roller 150 of the arm 146. In their inner or circuit controlling positions 119, the cams 113 on the members 96 engage the roller 150 on the lever 70 75 146 and move its free end rearwardly to the full line position as indicated in Fig. 4. This rearward movement of the lever 146 by a member 96 may be effected by a rotary movement of the lever 146 relative to a member 96 when the member 96 is in its inner position 119, in which

case the roller 150 rides over the cam 113, or it may be effected when the lever 146 comes to rest with the roller 150 radially aligned with one of the members 96 in its intermediate position 118 and the member 96 is subsequently moved to its inner position 119 by the lever 43, as previously described, in which case the member 96, in moving radially inwardly, engages the conical portion of the roller 150 and cams the free end of the lever 146 rearwardly.

One end of the switch operating rod 145 (Figs. 4 and 13), which is mounted for reciprocation within a central bore of the shaft 48, engages the finger-like portion 154 of the switch operating lever 146. The opposite end of the rod 145 is enlarged and engages a flat insulating member 158 secured to the intermediate portions of a pair of contact springs 160 and 161 of the switch 69. The contact springs 160 and 161, electrically connected in the telephone circuit (Fig. 16), are reciprocable through the movement of the rod 145 and are flexed to normally urge the rod 145 toward the left, as viewed in Fig. 4. When moved rearwardly, the contact springs 160 and 161 engage, respectively, contact springs 162 and 163 and close portions of the circuit to the transmitter and receiver (Fig. 16). The contact springs 160 and 161, when moved forwardly, open the telephone circuit through the contacts 162-163 to disconnect the transmitter and the receiver therefrom, and the contact spring 161, in its forward position, engages a contact spring 164 to connect the pulsing springs 26 and 27 into the circuit.

Thus the reciprocation of the switch operating lever 146, in response to the action of the cams 113, is transmitted through the rod 145 to actuate the contact springs 160-161 of the circuit control switch 69. At the end of a dialing operation and during the normal condition of the calling device, the pulsing springs 26 and 27 are disconnected from the line at the contacts 161-164 and the receiver and transmitter are connected in the line circuit by the engagement of the contacts 160-162 and 161-163, respectively. This is the condition obtaining when a cam 113 has effected the movement of the switch 69 to the position shown in the drawings (Figs. 4, 13 and 16). When the roller 150 of the switch operating lever 146 rides off the cam 113 and permits the spring contacts 160 and 161 to move forward after the production of the first pulse of each series of pulses, the pulsing contacts 26-27 are connected into the line by the contact springs 161-164 and the transmitter and receiver, respectively, are disconnected from line at the contact springs 162 and 163 (Fig. 16).

In dialing each digit of a called number, the dial 20 and the pulsing mechanism 23 are moved through arcs sufficient in length to actuate the pulsing contacts 26 and 27 a number of times equal to the digit dialed plus one. In other words, the dial and the pulsing mechanism are rotated to produce one pulse in excess of the number of the digit dialed. For example, when the digit "3" is dialed, the dial 20 and the pulsing mechanism 23 are rotated through an arc sufficient to produce four pulses. The pulsing spring contacts 26 and 27 are connected to the telephone circuit only during the period of transmission of the number of pulses equal to the number of the digit dialed; three in this case, and are disconnected from the circuit during the period of the one extra pulse. This provides an interval of

time between each series of pulses and insures the necessary time delay for the operation of the automatic switching mechanism in the central office when successive series of pulses are transmitted in rapid succession. Preferably, the pulsing contacts 26 and 27 are disconnected from the telephone circuit during the production of the first pulse of each series of pulses for each digit dialed and this is accomplished by the actuation of the circuit controlling switch 69 in response to the rearward movement of the switch operating lever 146 by the various actuating cams 113 which have been set to their inner positions 119. The stop and cam members 96-113 are set in predetermined positions in response to the actuation of the dial 20, as previously described, to cause the lever 146, at the end of each dialing operation, to stop in a position where the roller 150 will rest on one of the cams 113 in substantially the position indicated in Figs. 4, 7 and 15. Thus at the end of a complete dialing operation, the lever 146 will have been moved to its rearward position, as shown in full lines in Fig. 4, by one of the cams 113, and will have actuated the switch 69 to close the contact springs 161, 163 and 160, 162 in series, respectively, with the receiver and the transmitter, whereby the telephone circuit is in normal operating condition, as indicated in the diagram of Fig. 16.

The operation of the calling device will now be described. To dial the numeral or digit 5, for example, the person calling inserts his finger into the finger hole 28, opposite the numeral 5, and rotates the dial 20 in a clockwise direction until his finger engages stop 45, after which he withdraws his finger and the dial 20 is reversely rotated a short distance by the spring 22. The arcuate distance rotated by the dial in the dialing of the digit "5" is equal to six pulse-increments of movement or six times the 30° angular distance between adjacent finger holes 28 in the dial 20 plus the relatively short extra movement which is equal to the reverse movement of the dial at the end of the digit dialing movement. Assuming the parts to be in the position shown in Fig. 1 at the start of the dialing operation, as the dial 20 begins its clockwise rotation, the lever 43, rotating with the dial, engages the camming member 97 and imparts rotation thereto in unison with the movement of the dial 20. The roller 132 on the camming member 97, which, at the beginning of the dialing movement, as shown in Fig. 1, is holding the stop member 96 opposite the digit numeral 1 in its outer position 117 in engagement with the abutment member 95, is rotated with the dial 20 through six 30° pulsing increments and engages and cams six successive stop members 96 each to its radial outer position 117 until the roller 132 has come to rest, holding the stop member 96 opposite the digit numeral 7 in its outer position 117. As the roller 132 rides out from under the stop member 96 aligned with the numeral 1, that stop member 96 will be moved to its intermediate position 118 by the biased flexible arm 105 and disengage itself from the end 102 of the abutment member 95 which, being stressed for rotation by the torsion spring 22, starts to move in a clockwise direction, as viewed in Fig. 1, and continues until it engages a stop 96 moved into its path by the roller 132. If the rotary movement of the dial 20 is fast enough, the successive stop members 96 will be moved outwardly to their outer position 117 and then inwardly to their intermediate position 118 rapidly enough to prevent the stopping of the

governor-controlled rotary movement of the abutment member 95 until after the dial has completed its full digit dialing movement and the abutment member 95 engages the stop 96, which is aligned with the digit numeral "7" and has been moved to and held in its outer position 117 in the path of the abutment 95 by the roller 132. Thus it will be seen that in dialing the digit 5, the dial 20 is rotated through six pulse increments of 30° each to advance the operative stop 96 through six pulse-increments and permit the rotation of the spring driven abutment 95 and the pulsing mechanism associated therewith through a similar arc of movement of six pulse-increments, resulting in the production of six pulses.

When the person calling removes his finger from the finger hole 28 in the dial at the end of a digit dialing operation, the dial 20 and the lever 43 carried thereby are reversely rotated by the torsion spring 22, which reverse movement of the lever 43 and the dial 20 is arrested by the engagement of the lug 140 on the lever 43 with the adjacent stop member 96 disposed in its path of reverse movement. It will be understood that during dialing, the lug 140 on the lever 43 passes underneath the stop members 96 as the stop members are moved outwardly by the roller 132 of the camming member 97 as the member 97 is rotated by the lever 43 and that, as the stop members 96 are moved radially inwardly to their intermediate positions 118, they are positioned successively behind the lug 140. Therefore, when the lever 43 is moved in a reverse direction, the lug 140 will engage the stop member 96 in its path and the cam surface 141 on the lug 140 will engage the inclined surface 112 of the stop member 96 and cam the stop member rearwardly off the shoulder 124 of the arm 122 to a position where it is free to be moved to its radial inner position 119. Thus the stop member 96 immediately in back of the lug 140 of the lever 43 at the end of its digit dialing movement serves to limit the reverse movement of the lever 43 and the dial 20 and, by the camming action of the cam face 141 during its reverse movement, this stop member 96 is moved axially off the shoulder 124, after which it is moved radially to its inner position 119, in which position it is adapted to engage the roller 150 and effect the movement of the lever 146 to actuate the circuit control switch 69.

The rotatable portion of the pulsing mechanism 23 and the abutment member 95 carried thereby, being stressed for rotation in a clockwise direction by the torsion spring 22, will start to rotate when the stop member 96 engaging the abutment member 95 is disengaged therefrom and, as previously mentioned, will continue to rotate in a clockwise direction until the abutment member 95 is engaged and stopped by another stop member 96 moved into its path. At the beginning of the dialing operation, the roller 150 on the switch actuating lever 146, as shown in Figs. 1 and 4, is in engagement with the high point of a cam 113 on a stop member 96 moved to its inner position 119 and the cam 113 maintains the switch operating lever 146 in its rearward position and maintains the control switch 69 actuated in one direction to close the contact springs 160-162 and 161-163 and to open the contacts 161-164. With the control switch 69 in this position, the receiver and the transmitter are connected to the circuit and the pulsing contacts 26 and 27 are disconnected from the circuit. As the pulsing mechanism rotates at a speed con-

trolled by the governor 70, the teeth 61 on the pulsing wheel 24, at regular intervals, will actuate the pulsing contact springs 26 and 27 to produce a series of pulses. The roller 150 riding on the cam 113 of the inwardly positioned stop member 96 serves to maintain the actuating lever 146 and the control switch 69 in the position with the spring contacts 160-162 and 161-163 closed and the spring contacts 161-164 open, as indicated on the drawings, until the first of the series of pulses has been produced, after which the roller 150 rides off the cam 113 and permits the actuating lever 146 to flex to its forward position and effect the actuation of the control switch 69 in the opposite direction to open the spring contacts 160-162 and 161-163 and close the spring contacts 161-164. This actuation of the switch 69 in the reverse direction serves to disconnect the receiver and the transmitter from the line and connect the pulsing contacts 26 and 27 to the line while the remainder of the pulses of the series are produced by the pulsing mechanism. Thus, of the six pulses produced by this dialing operation, the first is not transmitted because the pulsing contacts 26 and 27 are disconnected from the line during its production, whereas the remaining five pulses are transmitted because, during their production, the pulsing contacts 26 and 27 are connected to the line. The roller 150 on the lever 146 near the end of its arc of movement and after the series of pulses has been transmitted, will engage the cam 113 of a stop member 96 moved to its inner position 119 at digit numeral 8 and will be cammed rearwardly to actuate the control switch 69 to disconnect the pulsing contacts 26 and 27 from the line and reconnect the transmitter and the receiver to the line before the roller comes to rest on the cam surface 113.

The remaining digits of the called number are dialed in a manner similar to the first just described. For example, if the second digit of the called number is 2, the person calling will insert his finger in the finger hole 28 of the dial 20 opposite the digit numeral 2 and rotate the dial clockwise until his finger engages the stop 45. The dial 20 is thus moved through three pulse-increments of 30° each plus a little extra and the camming member 97 and the roller 132 are moved through three pulse-increments, which movement of the roller 132 permits the disengagement of the operative stop 96 from the abutment member 95 and effectively advances the operative stop member three pulse-increments, thereby permitting the abutment member 95 and the pulsing mechanism to rotate three pulse-increments and effect the production of three pulses. The circuit control switch 69, which at the beginning of the digit dialing movement is positioned so that the transmitter and the receiver are connected to the telephone circuit and the pulsing contacts 26 and 27 are disconnected from the circuit, is maintained in this position by the roller 150 of the lever 146 riding on the cam 113 while the first pulse of the digit series is produced, after which the roller 150 rides off the cam 113 to permit the lever 146 and the control switch 69 to be actuated in the forward direction to connect the pulsing contacts 26 and 27 to the circuit and disconnect the transmitter and receiver from the circuit during the transmission of the two remaining pulses of the series. When the person calling removes his finger from the finger hole at the end of the digit dialing movement, the dial 20 and the lever 43 movable therewith

are moved a short distance in a reverse direction. The lug 140 of the lever 43 engages the stop member 96 in its path of reverse movement and effects the movement of the stop 96 from its intermediate position to its inner position 119, in which position the cam 113 on the member 96 will engage and move the roller 150 and the lever 146 which, in turn, will actuate the circuit control switch 69 in a forward direction to disconnect the pulsing contacts 26 and 27 from the telephone circuit and to reconnect the transmitter and the receiver to the circuit.

When the dial 20 is rotated rapidly to dial a digit of a called number, the operative stop member 96 engaging the abutment 95 is withdrawn therefrom and is effectively rotated a distance equal to the angular movement of the dial 20 and with substantially the same rate of movement as that of the dial and the relatively movable governor-controlled pulsing mechanism 23 is caused to rotate in a clockwise direction. Before the abutment member 95 of the pulsing mechanism 23 advances to and engages the operative stop member 96 in its path, a second digit may be rapidly dialed, which effectively advances the operative stop an angular distance equal to the angular second-digit-dialing movement of the dial 20 and serves to keep the operative stop member 96 in advance of the abutment member 95. The remaining digits of the calling number may be dialed rapidly in a similar manner while the abutment member 95 and the pulsing mechanism 23 are rotating at the governor-controlled speed and this will result in the dialing operation being completed before the completion of the rotation of the pulsing mechanism 23.

When the dialing of the number is rapidly completed, the rotation of the pulsing mechanism starts at the beginning of the dialing operation and continues to its completion at an even rate of movement controlled by the governor. The pulses are thus continuously produced at regular intervals from the beginning to the completion of the pulsing operation, from the first digit series to the last digit series of pulses of the number being dialed, and the pulsing contacts 26 and 27 are connected to the telephone circuit by the circuit controlling means on completion of the first pulse of each digit-series of pulses and disconnected therefrom on completion of the last pulse of each digit-series of pulses. The pulsing contacts 26, 27 are thus disconnected from the line circuit at the beginning of and at the end of each number dialing operation and they are disconnected for an interval of one pulse, the first pulse, in each digit-series of pulses of the number called.

With the improved dialing apparatus herein disclosed, a party calling a number may rotate the finger wheel with great rapidity to dial succeeding digits of the called number and have the finger wheel set up or condition means in the device to transmit at an even and controlled rate the successive series of digit-pulses of the called number and in spaced relation one series of pulses to another.

What is claimed is:

1. In a telephone calling device, pulsing contacts, means rotatable in one direction only for actuating said pulsing contacts to produce a pulse for each predetermined arc of movement thereof, spring means for stressing said actuating means for rotation in said one direction, a governor for controlling the speed of said actuating

means, non-rotatable stop means to stop said actuating means in any one of a plurality of predetermined positions, and dialing means for actuating said non-rotatable stop means to start said actuating means in response to the rotation of the dialing means and to stop said actuating means in a predetermined relation to said dialing means whereby the rotatable actuating means is rotated through a predetermined arc to produce 10 a predetermined number of pulses as determined by the rotary movement of the dialing means.

2. In a telephone calling device, pulsing means including a wheel rotatable in one direction only and capable of producing a predetermined number of regularly spaced pulses for each revolution thereof, a plurality of non-rotatable normally inoperative stop members capable of stopping said wheel in a plurality of positions whereby said wheel may be stopped after the production of 15 various predetermined numbers of pulses, a dial coaxially aligned with said wheel and rotatable in said one direction through dialing movements of various predetermined lengths and movable in a reverse direction through a relatively short distance at the end of each dialing movement, spring means urging said dial and said wheel for rotation in opposite directions, a governor connected to said wheel for controlling the speed thereof, means rotatable with said dial for rendering successive ones of said stop members operative to 20 stop said rotatable wheel after a predetermined movement thereof as determined by the movement of said dial, and means rotatable with said dial and engageable with said stop members for 25 limiting the reverse movement of said dial.

3. In a telephone calling device, the combination of pulsing means including a wheel rotatable in one direction only and capable of producing a predetermined number of pulses at regular 30 intervals for each revolution thereof, a plurality of movable normally ineffective stop members adapted to stop said wheel in a plurality of positions whereby said wheel may be stopped after various predetermined movements and the production of various predetermined numbers of pulses, spring means for rotating said wheel in said one direction, a governor associated with said wheel for controlling the speed thereof, a dial selectively operable in said one direction only 35 through various arcs of predetermined lengths, and means rotatable with said dial for actuating successive stop members to render one of said stop members effective to stop said wheel after a predetermined movement thereof as determined by the movement of said dial.

4. In a telephone calling device, the combination of a dial rotatable in one direction through dialing movements of various lengths, pulsing contacts, means including a rotatable member for actuating said contacts, spring means interconnecting said dial and said rotatable member for stressing said member and said dial for rotation in opposite directions, a governor connected with said rotatable member, a plurality of stop members movable to a plurality of adjusted positions, said stop members acting in one of their positions to limit the reverse movement of said dial, and dial actuated means operable in response to each dialing movement of said dial to render a 45 selected one of said stop members effective to stop the pulsing wheel in a predetermined position relative to said dial.

5. A telephone calling device comprising a dial rotatable in one direction through dialing movements of various predetermined lengths and

movable in a reverse direction through a relatively short distance at the end of each dialing movement, pulsing contacts, a pulsing wheel rotatable in one direction for actuating said pulsing contacts to produce a predetermined number of pulses at regular intervals for each revolution thereof, means for supporting said dial and said wheel for rotation about a common axis, spring means for stressing said pulsing wheel and said dial for rotation in opposite directions, a 10 governor connected to said wheel, a stop element rotatable with said wheel, a plurality of movable non-rotatable stop members adapted to engage said element and stop said wheel in a plurality of positions, means rotatable with the dial for moving successive stop members from a first to a second position to render one of said members operative to engage said stop element and stop said pulsing wheel after a predetermined rotation thereof determined by the dialing movement of the dial, said means including an arm engageable with the stop members in said first position to limit the reverse movement of said dial, and means for returning said stop members from said second position to said first position.

6. In a telephone calling device, pulsing contacts, a pulsing wheel for actuating said contacts, a governor for controlling the speed of said wheel, a dial operatively associated with the pulsing wheel to effect the rotation thereof, a plurality of movable members each settable in a plurality of positions, dial actuated means for selectively setting said movable members, and means rotatable in timed relation with the pulsing wheel and operable under control of said members in one of said set positions for rendering the pulsing contacts ineffective.

7. In a telephone calling device, the combination of a dial rotatable in one direction through dialing movements of various lengths and movable in a reverse direction through a relatively short distance at the end of each dialing movement, pulsing means including a pulsing member operatively connected to said dial and rotatable through arcuate movements determined by the dialing movements of said dial for producing a series of pulses for each of said arcuate movements, a plurality of inoperative cam members, dial actuated means operable in response to the reverse movements of said dial to render selected ones of said cam members operative, and means rotatable in timed relation to said pulsing member and under control of said operative cam members for rendering said pulsing means ineffective for one pulse in each series of pulses produced.

8. In a telephone calling device, a dial rotatable in one direction through dialing movements of various lengths and movable a relatively short distance in a reverse direction at the end of each dialing movement, pulsing contacts connectible to a calling circuit, means for actuating said pulsing contacts including a member operatively connected to said dial and rotatable through rotary movements determined by the dialing movements of said dial for producing a series of pulses for each of said rotary movements, a plurality of normally inoperative cam members, dial actuated means operable in response to the reverse movements of said dial to render selected ones of said cam members operative, and switch means including an element rotatable in timed relation to said rotatable pulsing member and actuatable by said operative cam members to connect the pulsing contacts to said calling circuit for all of the pulses except one in each series

of pulses and for disconnecting the pulsing contacts from the calling circuit for said one pulse in each of said series of pulses.

9. A telephone calling device comprising a dial 5 rotatable in one direction through dialing movements of various lengths and reversely movable through a relatively short distance at the end of each dialing movement, means for limiting the reverse movements of said dial, pulsing contacts, a rotatable pulsing wheel yieldably connected to said dial for rotation in said one direction in response to dialing movements of said dial to actuate said pulsing contact, a governor for controlling the speed of said pulsing wheel, dial actuated means operable in response to dialing movements of said dial for limiting the lengths of the rotary movements of said rotatable pulsing wheel to substantially the lengths of the dialing movements of said dial, and means including 15 means conditioned in response to the reverse movements of said dial to render the pulsing contacts ineffective during a portion of each movement of the pulsing wheel imparted thereto by and corresponding to the dialing movements of said dial.

10. A telephone calling device comprising a dial rotatable in one direction through dialing movements of various predetermined lengths and movable in a reverse direction through a relatively short distance at the end of each dialing movement, means for limiting the reverse movements of said dial, pulsing means including a member coaxially aligned with said dial and rotatable only in said one direction capable of producing a pulse 30 for each predetermined arc of movement thereof, spring means for stressing said member and said dial for rotation in opposite directions, a governor associated with said rotatable member to control the speed thereof, dial actuated means operable in response to the dialing movements of said dial to effect the starting of the rotatable member and to stop said member in a predetermined position with respect to said dial whereby the rotatable member may be moved through various 35 predetermined arcs to produce various predetermined series of pulses as determined by the dialing movement of said dial, and means including normally inoperative actuating means selectively rendered operable in response to the reverse 40 movement of said dial to render ineffective one of the pulses in each series of the pulses produced.

11. A telephone calling device comprising a dial rotatable in one direction through dialing movements of various predetermined lengths and movable a relatively short distance in a reverse direction at the end of each dialing movement, pulsing contacts electrically connectible to a telephone circuit, rotatable means for actuating said pulsing contacts, spring means for stressing said pulsing contacts, a plurality of stop members settable in a plurality of positions and operable in one of said positions to limit the reverse movement of said dial, dial controlled means operable in response to the dialing movements of the dial to move selected ones of said stop members in a second position and operable in response to the reverse movements of the dial to set selected ones of said stops in a third position, said stop members in said second position serving to stop the rotatable pulsing means in a predetermined position with respect to the dial, switch means connecting the pulsing contacts to the telephone circuit, and

means rotatably associated with said rotatable means and operable under control of said stop members set in said third position to actuate said switch means to disconnect the pulsing contacts from the calling circuit for an interval of one pulse.

12. A telephone calling device comprising a dial rotatable in one direction through dialing movements of various lengths and movable a relatively short distance in a reverse direction at the end of each dialing movement, pulsing contacts, a rotatable pulsing wheel for actuating said pulsing contacts, spring means for stressing the pulsing wheel and the dial for rotation in opposite directions, a governor associated with said pulsing wheel to control the speed thereof, a plurality of stop members settable in a plurality of positions, dial controlled means operable in response to the dialing movements of said dial for moving selected ones of said stops in one position and operable in response to the reverse movements of said dial to said set selected ones of said stops in another position, said stop members cooperating with said dial controlled means to limit the reverse movement of said dial, said stops set in said one position serving to stop said pulsing wheel in a predetermined relation to said dial, and means rotatable in timed relation with the pulsing wheel and operable under control of the stop members in said other position for rendering the pulsing contacts ineffective for an interval of one pulse.

13. A telephone calling device comprising a dial rotatable in one direction through dialing movements of various predetermined lengths and movable a relatively short distance in a reverse direction at the end of each dialing movement, a plurality of adjustable stop members, means actuated by said dial in response to each dialing movement for moving a selected one of said stop members in one position and in response to each reverse movement for setting a selected one of said stop members in another position, pulsing means including a rotatable member operatively connected to the dial and rotatable in said one direction to produce a predetermined number of pulses at regular intervals for each revolution of the member, said stops in said one position operating to stop the rotatable member in a predetermined relation to said dial whereby said rotatable member may be rotated through various predetermined arcs to produce various predetermined series of pulses as determined by the dialing movements of said dial, and means rotatable in timed relation with said rotatable member and under control of the stops in said other position to render said pulsing means ineffective during the production of one pulse of each of said series of pulses produced.

14. A calling device for use with a telephone in an automatic telephone system comprising a dial rotatable in one direction through dialing movements of various lengths and movable a relatively short distance in a reverse direction at the end of each dialing movement, means for limiting the reverse movement of said dial, pulsing contacts, rotatable pulsing means for actuating said pulsing contacts, spring means for stressing the pulsing means and the dial for rotation in opposite directions, a governor associated with said pulsing means to control the speed thereof, dial controlled means operable in response to each dialing movement for starting the rotation of said pulsing means and for stopping said rotatable pulsing means in a predetermined relation

to said dial, a plurality of normally ineffective cam members, dial controlled means operable in response to the reverse movements of said dial to render selected ones of said cams effective, switch means operable in one position to effectively connect said pulsing contacts to and disconnect the telephone from the telephone system and in a second position to disconnect said pulsing contacts from and reconnect the telephone to the telephone system, and means including an element rotatable in timed relation with said rotatable pulsing means operable under control of said effective cam members to actuate said switch means.

15. A telephone calling device comprising pulsing means including a wheel rotatable in one direction only for producing a pulse for each pulse-increment of rotation of predetermined length of said wheel, a dial selectively rotatable in said one direction only through dialing movements of various predetermined lengths and operatively connected to said wheel to effect the rotation of said wheel through various series of pulse-increments for producing various series of pulses, means for moving said dial in a reverse direction at the end of each dialing movement, means for limiting the reverse movement of said dial to a relatively short distance, and means operable in response to the reverse movement of said dial to render ineffective a pulse of each series of pulses produced.

16. A telephone calling device comprising pulsing contacts, means including a wheel rotatable in one direction only for actuating said pulsing contacts to produce a pulse for each pulse-increment of rotation of a predetermined length of said wheel, spring means for rotating said wheel in said one direction, stop means capable of stopping said wheel after each pulse-increment of rotation, dialing means selectively rotatable in said one direction only through dialing movements of various predetermined lengths for selectively actuating said stop means to effect the rotation of said wheel through various series of pulse-increments for producing various series of pulses, means for moving said dialing means in a reverse direction at the end of each dialing movement, means for limiting the reverse movement of said dialing means to a relatively short distance, and means operable in response to the reverse movement of said dialing means for rendering ineffective one pulse of each series of pulses produced.

17. A telephone calling device comprising a dial rotatable in one direction through dialing movements of various predetermined lengths and movable in a reverse direction through a relatively short distance at the end of each dialing movement, pulsing contacts, a pulsing wheel rotatable in one direction for actuating said pulsing contacts a predetermined number of times at regular intervals for each revolution thereof, means for supporting said dial and said wheel for rotation about a common axis, spring means for stressing said pulsing wheel and said dial for rotation in opposite directions, a governor for said wheel, a stop element rotatable with said wheel, a plurality of movable stop members operable to engage the said stop element in a plurality of positions and capable of stopping said wheel after the production of each pulse, means rotatable with the dial for moving successive stop members from a first to a second position to render one of said stop members operative to engage said stop element and said pulsing wheel in a

predetermined relation to said dial, means for returning said stop members from said second position to said first position, means rotatable with said dial and engageable with said stop members for limiting the reverse movement of said dial and for selectively moving said stop members to a third position, and means including a member rotatable in timed relation to said pulsing wheel and actuatable by said stop members in said third position to render said pulsing contacts ineffective.

18. In a calling device, the combination of a dial rotatable in one direction only through dialing movements of various lengths, pulsing contacts, means including a member rotatable in one direction only for producing a plurality of regularly spaced pulses for each revolution of said member, spring means for stressing said member for rotation in said one direction, a governor operatively connected to said rotatable member, stop means for stopping said member in a predetermined relation to said dial, and means for effectively advancing said stop means in response to the dialing movements of said dial to initiate rotation of said member and to limit the rotation of said member to arcs corresponding to the dialing movements of said dial.

19. In a telephone calling device, the combination of a dial rotatable in one direction only and freely movable in said one direction through dialing movements of various lengths, pulsing means including a governor controlled member rotatable in one direction only for producing a plurality of regularly spaced pulses for each revolution of said rotatable member, means interconnecting said dial and said pulsing means for rotating said member through arcs corresponding to the dialing movement of said dial in response to and simultaneously with said dialing movements, and dial controlled means for rendering said pulsing means ineffective during a portion of each arc of rotation imparted to said rotatable member by said dial.

20. In a calling device, the combination of pulsing contacts, means including a member rotatable in one direction only for producing a pulse for each predetermined arc of rotation thereof, a governor operatively connected to said rotatable member for controlling the speed thereof, a dial rotatable in one direction only and freely actuatable in said direction through dialing movements of various lengths, means including a yieldable element interconnecting said dial and said rotary member for rotating said rotatable member through arcs proportional to the dialing movement of said dial in response to and simultaneously with said dialing movements, and dial controlled means for rendering said pulsing contacts ineffective during a portion of each arc of rotation imparted to said rotatable member by said dial.

21. In a telephone calling device, the combination of pulsing contacts, means including a member rotatable in one direction only for actuating said contacts to produce a pulse for each predetermined arc of rotation thereof, a governor operatively connected to said rotatable member for controlling the speed thereof, a dial rotatable in one direction only and freely movable in said one direction through dialing movements of various lengths, a yieldable drive means interconnecting said dial and said rotatable member for rotating said rotatable member in response to and simultaneously with dialing movements of

said dial, and dial controlled means operable to initiate the rotation of said member and to stop said rotatable member after arcuate movements thereof corresponding to the dialing movements of said dial.

22. In a telephone calling device, the combination of pulsing contacts, means including a member rotatable in one direction only for actuating said contacts to produce a pulse for each predetermined arc of rotation thereof, a governor operatively connected to said rotatable member for controlling the speed thereof, a dial rotatable in one direction only and freely movable in said one direction through dialing movements of various lengths, a yieldable drive means interconnecting said dial and said rotatable member for rotating said rotatable member in response to and simultaneously with dialing movements of said dial, dial controlled means operable to initiate the rotation of said member and to stop said rotatable member after arcuate movements thereof corresponding to the dialing movements of said dial, and dial controlled means for rendering said pulsing contacts ineffective during a portion of each arc of rotation imparted to said rotatable member by said dial.

23. In a telephone calling device, the combination of a dial freely rotatable in one direction through dialing movements of various lengths, pulsing contacts, a toothed pulsing wheel for actuating said contacts, means rotatably supporting said dial and said pulsing wheel in axial alignment, a spring operatively connected to said dial for stressing said pulsing wheel for rotation in said one direction, a governor for controlling the rotation of said pulsing wheel, a plurality of normally ineffective stop members operable to stop said wheel after each pulse movement thereof, and dial actuated means operable in response to each dialing movement of said dial to render a selected one of said stop members effective to stop the pulsing wheel in a predetermined position relative to said dial.

24. In a telephone calling device, a dial rotatable in one direction only through dialing movements of various lengths, pulsing contacts, means including a wheel rotatable in one direction only to actuate said pulsing contacts for producing a plurality of regularly spaced pulses for each revolution of said wheel, spring means stressing said wheel for rotation in said one direction, a governor operatively connected to said wheel, stop means for stopping said wheel in a predetermined position relative to said dial, means operable in response to the movement of said dial for effectively advancing said stop means to initiate the rotation of said wheel and to stop said wheel after an arcuate movement thereof corresponding to the dialing movement of said dial, a plurality of normally inoperative cam members, dial actuated means for selectively rendering one of said cam members operative for each dialing movement of said dial, and switch means including means rotatable in timed relation to said wheel and actuated by said operative cam members for rendering the pulsing contacts inoperative for a portion of each arc of movement of said wheel imparted thereto in response to the dialing movements of said dial.

25. In a telephone calling device, pulsing contacts connectible to a calling circuit, governor-controlled means including a member rotatable in one direction only for actuating said pulsing contacts to produce a predetermined number of regularly spaced pulses for each rotation of said

21

member, a dial rotatable in said one direction only and freely movable through dialing movements of various lengths, means interconnecting said dial and said rotary member for imparting arcuate movements to said member in response to and simultaneously with dialing movements of said dial and corresponding in length to said dialing movements, and means for connecting said pulsing contacts to the calling circuit for a portion of each arcuate movement of said rotatable member imparted thereto by said dial and for disconnecting said pulsing contacts from the calling circuit for a predetermined interval at one end of each arcuate movement of said rotatable member.

26. In a calling device for use with a telephone in a calling circuit, pulsing contacts connectible to said calling circuit, means including a member rotatable in one direction only for actuating said pulsing contacts to produce a predetermined number of regularly spaced pulses for each revolution of said member, spring means for stressing said member for rotation in said one direction, a governor operatively connected to said rotatable member, a dial rotatable in said one direction only and freely movable through dialing movements of various lengths, means supporting said dial and said rotatable member for rotation about a common axis, stop means capable of stopping said rotatable member after production 30

22

of each pulse, means operable in response to the movement of said dial for effectively advancing said stop means to initiate the rotation of said rotatable member and to stop said member in a predetermined relation to said dial, a plurality of normally inoperative cam members, dial actuated means for selectively rendering one of said cam members operative for each dialing movement of said dial, and switch means including means rotatable in timed relation to said rotatable member and in cooperation with said operative cam members for connecting the pulsing contacts to said calling circuit and simultaneously disconnecting the telephone from the calling circuit for a portion of each arcuate movement of said rotatable member imparted thereto by said dial and for reconnecting said telephone to the calling circuit and for disconnecting said pulsing contacts from the calling circuit for a predetermined interval at one end of each arcuate movement of said rotatable member.
